MOUNTING FOR PLAYER ARMS

Mahlon W. Kenney, Oak Park, Ill., assignor to
 J. P. Seeburg Corporation, Chicago, Ill., a corporation of Illinois

Application April 21, 1947, Serial No. 742,924

4 Claims. (Cl. 274—23)

1

This invention relates to player arms or tone arms for phonographs. These arms require pivotal supports on two axes. One arm is parallel to the turntable axis to permit movement of the pickup across the record as the stylus follows the groove. The other axis is at right angles to the first mentioned axis to permit movement of the stylus away from and towards the record. This second axis enables the player arm to be raised from, and lowered to, the record, either manually or automatically, and also provides for vertical movement of the pickup during the playing of a record.

Usually, during the playing of the record, the pickup moves up and down continuously to a slight extent due to slight obliquity of the turntable or due to one or more of the records on the turntable being warped. The usual type of bearing which provides this axis is a pin carried by one member which extends through openings in another member. Since the movement of the player arm must be relatively free, the pin is normally provided with relatively large openings. Nevertheless, the friction of such a bearing amounts to between four and nine grams, measured at the needle, and is seldom less than four grams. In the case of a pickup having a low nominal needle pressure, for example, around one ounce or one-half ounce, the needle pressure actually varies by a large percentage. This results in excessive wear on the record grooves and failure of the stylus to follow the record groove perfectly with resultant distortion in the audible reproduction. Furthermore, the loose fit of the bearing permits vibration of the player arm in its plane parallel to the record, thus introducing further distortion into the audible reproduction.

In accordance with the present invention, I provide for the vertical movement of the player arm, a knife edge pivot. This knife edge pivot cooperates with members providing V-shaped recesses. In order to insure a perfect V-shaped recess, I employ two adjacent strips cut obliquely in opposite directions. It is easy to obtain a straight edge on a strip and that is all that is necessary to obtain a perfect V-shaped recess.

In the embodiment of the invention hereinabove described and illustrated, I provide the elements constituting the V-shaped recesses on the player arm and the knife edge on the element which pivotally supports the player arm. It must be understood however, that this relation may be reversed in accordance with the present invention.

2

The present invention will be readily understood from the following description of a preferred embodiment thereof, taken in conjunction with the accompanying drawings in which:

- 5 Figure 1 is an inverted plan view of a player arm embodying my invention;
 Fig. 2 is a fragmentary sectional elevational view therethrough, taken on the line 2—2 of Figure 1;
 10 Fig. 3 is an elevational view of the knife edge member;
 Fig. 4 is a perspective view of the elements providing the V-shaped recesses, and associated elements; and
 15 Fig. 5 is a perspective of a clamping member employed in the assembly.
 Referring to the drawings, the reference numeral 10 designates the player arm, which carries a pickup 11, including a stylus 12. The player arm 10 is pivotally supported on a support 13 which is integral with a sleeve 14. The sleeve 14 is pivotally supported in a vertical standard 15 so as to provide the vertical axis for the movement of the player arm across the record. Where the player arm is employed in an automatic phonograph or record changer, the player arm may be raised, in known manner, by a pin 16 which extends through the sleeve 14 and engages an adjustable screw 17 carried by the player arm. When the player arm is in operation, the pin 16 is retracted so that the stylus rests upon the record being played. The support 13 is provided with an upturned portion 18 to which is secured, for example, by means of rivets 19, a knife edge member 20. As best seen in Fig. 3, the knife edge member 20 is of general T-shape, providing projecting arms 21 which cooperate with the V-shaped recesses carried by the player arm 10.

- 40 The V-shaped recesses are established by two U-shaped elements 22 and 23, dimensioned so that the member 22 fits into the member 23 as shown in Fig. 4. The legs of the members 22 and 23 are provided with oblique edges 24 and 25 which intersect when the member 22 is assembled within the member 23. The members 22 and 23 are rigidly mounted on the player arm 10 so that the V-shaped recesses are directed downwardly to cooperate with the ends 50 of the knife edge member 20 carried by the support 13, as shown in Fig. 2. The player arm 10 is provided with depending shouldered elements 26 which provide four corner supports for the U-shaped members 22 and 23. Preferably, 55 the bases of the U-shaped members 22 and 23

are provided with aligned openings through which depends a tapered post 27 carried by the player arm 10. The U-shaped members 22 and 23 may suitably be firmly seated on the player arm by means of a lockwasher 28 which bears against the bases of the U-shaped members and is provided with gripping tongues 29 which tend to dig into the post 27.

To secure the player arm to the support 13, I provide the clamping member 30 shown in Fig. 5. This member is secured to the player arm by means of a screw 31 and it is provided with two legs 32 and 33 which extend below the arms 21 of the knife edge member 20 when the clamping member is assembled on the player arm.

Between each pair of depending shouldered elements, I provide recesses 34 so that the arms 21 of the knife edge member may project beyond the members 22 and 23. An abutment 35 on the support 13 is arranged to engage a shoulder 36 on the player arm 10 to limit the downward movement of the player arm. The weight of the player arm may be counterbalanced to give the desired needle pressure by means of a spring 37 which is connected to an arm 38 rigid with the support 13, and to the player arm 10. This spring may suitably be connected to the washer 28 and I provide a slot 39 in the post 27 to accommodate the upper end of the spring. The adjustable screw 17 may suitably be carried by a nut 40 carried by the clamping member 30.

As indicated by the dot and dash lines in Figure 1, the axis provided by the knife edge member 20 is substantially at right angles to the longitudinal direction of the pickup and stylus. Consequently, the player arm can co-operate with records on the turntable at various elevations without substantial displacement of the pickup about its longitudinal axis.

My improved player arm has a practically geometrically perfect bearing. It has substantially zero friction. The friction cannot be detected with the instruments which indicate between four and nine grams with conventional bearings. The spring 37 assists the weight of the player arm in keeping the knife edge seated in the V-shaped recesses provided by the edges 24 and 25. Since these recesses are geometrically perfect, the player arm is precisely mounted relative to the member 31 so that the stylus always lands on the record at correct initial position when the player arm is incorporated in an automatic phonograph.

Although the invention has been described in connection with the specific details of a preferred embodiment thereof, it must be understood that the invention is not intended to be limitative to such details except insofar as set forth in the accompanying claims.

Having thus described my invention, I declare that what I claim is:

1. In a player arm assembly for phonographs comprising a player arm element and a supporting element carrying said player arm element, in combination, a knife edged member carried by one element, a pair of U-shaped members, and means securing said U-shaped members to the other element in nested relation, the adjacent legs of the U-shaped members having relatively oblique edges which intersect in said nested relation to provide V-shaped recesses for the reception of said knife edged member.
2. In a player arm assembly for phonographs comprising a player arm element and a supporting element carrying said player arm element, in combination, a knife edged member carried by one element, a pair of U-shaped members, means securing said U-shaped members to the other element in nested relation, the adjacent legs of the U-shaped members having relatively oblique edges which intersect in said nested relation to provide V-shaped recesses for the reception of said knife edged member, and means carried by said other element extending across said knife edged member to retain it in said recesses.
3. In a player arm assembly for phonographs comprising a player arm and a supporting member carrying said player arm, in combination, a knife edged member carried by said supporting member, and a pair of U-shaped members, and means securing said U-shaped members to the player arm in nested relation, the adjacent legs of the U-shaped members having relatively oblique edges which intersect in said nested relation to provide V-shaped recesses for the reception of said knife edged member.
4. In a player arm assembly for phonographs comprising a player arm and a supporting member carrying said player arm, in combination, a knife edged member carried by said supporting member, a pair of U-shaped members, means securing said U-shaped members to the player arm in nested relation, the adjacent legs of the U-shaped members having relatively oblique edges which intersect in said nested relation to provide V-shaped recesses for the reception of said knife edged member, and means carried by the player arm extending across said knife edged member to retain it in said recesses.

MAHLON W. KENNEY.
